UNITED STATES PATENT OFFICE

118,572

DESIGN FOR A CLOTHING CLEANING MACHINE

Karl Schultz, Detroit, Mich.

Application April 17, 1939, Serial No. 84,355

Term of patent 3½ years

To all whom it may concern:

Be it known that I, Karl Schultz, a citizen of the United States of America, residing at Detroit, in the county of Wayne and State of Michigan, have invented a certain new, original, and ornamental Design for a Clothing Cleaning Machine, of which the following is a specification, reference being had therein to the accompanying drawing forming a part thereof, in which

ing cleaning machine embodying my new design; and Figure 2 is a view in front perspective thereof.

The dominant features of my design reside in the portions shown in full lines.

I claim:

The ornamental design for a clothing cleaning machine, substantially as shown and described.

KARL SCHULTZ.
